OTHER PUBLICATIONS

U.S. Appl. No. 29/577,378, filed Sep. 13, 2016 of Amarasinghe et al. for "Frame Module for Patient Interface," (parent).

Primary Examiner — Barbara Fox

Assistant Examiner — Lilyana Bekic

(74) *Attorney, Agent, or Firm* — Nixon & Vanderhye P.C.

(57) **CLAIM**

The ornamental design for a headgear for patient interface, as shown and described.

DESCRIPTION

FIG. 1 is a front perspective view of a headgear for patient interface according to a first embodiment of our new ornamental design;

FIG. 2 is a front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof;

FIG. 8 is a rear perspective view of a headgear for patient interface according to a second embodiment of our new ornamental design;

FIG. 9 is a rear view thereof;

FIG. 10 is a front view thereof;

FIG. 11 is a top view thereof;

FIG. 12 is a bottom view thereof;

FIG. 13 is a right side view thereof;

FIG. 14 is a left side view thereof;

FIG. 15 is a front perspective view of a headgear for patient interface according to an third embodiment of our new ornamental design;

FIG. 16 is a front view thereof;

FIG. 17 is a rear view thereof;

FIG. 18 is a top view thereof;

FIG. 19 is a bottom view thereof;

FIG. 20 is a right side view thereof;

FIG. 21 is a left side view thereof;

FIG. 22 is a rear perspective view of a headgear for patient interface according to a fourth embodiment of our new ornamental design;

FIG. 23 is a rear view thereof;

FIG. 24 is a front view thereof;

FIG. 25 is a top view thereof;

FIG. 26 is a bottom view thereof;

(Continued)

FIG. 27 is a right side view thereof; and,
 FIG. 28 is a left side view thereof.
 Line shading and hatched lines have been used in the
 drawings to indicate a contrast in appearance as shown.
